US0D1074307S

(12) **United States Design Patent** (10) Patent No.: **US D1,074,307 S**
(45) Date of Patent: ** May 13, 2025

(54) **FOODSTUFF UTENSIL**

(71) Applicant: **Chef Robotics, Inc.**, San Francisco, CA (US)

(72) Inventors: **Xinyi Daniel Tang**, San Francisco, CA (US); **John Unkovic**, San Francisco, CA (US); **Rajat Bhageria**, San Francisco, CA (US); **Kody Brown**, San Francisco, CA (US)

(73) Assignee: **Chef Robotics, Inc.**, San Francisco, CA (US)

(**) Term: **15 Years**

(21) Appl. No.: **29/873,689**

(22) Filed: **Apr. 5, 2023**

(51) LOC (15) Cl. **31-00**

(52) U.S. Cl.

USPC **D7/412**; D15/199

(57) **CLAIM**

The ornamental design for a foodstuff utensil as shown and described.

DESCRIPTION

FIG. 1 is an isometric view, from the front top left, of a foodstuff utensil, showing our new design;

FIG. 2 is an isometric view, from the back bottom right thereof;

FIG. 3 is an elevation view from the left thereof;

FIG. 4 is an elevation view from the right thereof;

FIG. 5 is an elevation view from the front thereof;

FIG. 6 is an elevation view from the back thereof;

FIG. 7 is a plan view from the top thereof; and,

FIG. 8 is a plan view from the bottom.

1 Claim, 6 Drawing Sheets
